ELECTRICAL INSTRUMENT CONSOLE

Louis W. Erath, Houston, Tex., assignor to Test Equipment Corporation, Houston, Tex., a corporation of Texas

Filed May 9, 1962, Ser. No. 70,050

Term of patent 14 years

(Cl. D26—1)

Fig. 2

Fig. 3

FIG. 1 is a front perspective view of an electrical instrument console, showing my new design;

FIG. 2 is a side elevational view thereof, the side opposite being a mirror image thereof; and

FIG. 3 is a rear elevational view.

The essential features of my design reside in the portions shown in solid lines.

I claim:

The ornamental design for an electrical instrument console, as shown and described.
